UNITED STATES PATENT OFFICE.

WILLIAM PRESTON STUNZ, OF LANSDOWNE, MARYLAND, ASSIGNOR TO GEORGE REGESTER WEBB, OF BALTIMORE, MARYLAND.

TELEPHONE INSTRUMENT.

1,030,550.

Specification of Letters Patent.

Patented June 25, 1912.

Application filed September 29, 1910. Serial No. 584,570.

To all whom it may concern:

Be it known that I, WILLIAM PRESTON STUNZ, a citizen of the United States, residing at Lansdowne, in the county of Baltimore and State of Maryland, have invented certain new and useful Improvements in Telephone Instruments; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to telephonic instruments, and has for its particular object to improve the quality in tone, volume and distinctness of the sound waves carried to a receiver from a transmitter or other source of origin; also to provide a telephonic instrument in which the diaphragm is normally under the pressure of a lever influenced by variation in an electric circuit or magnetic strain whereby the diaphragm is rendered more sensitive and is more quickly responsive to vibrations received through or imparted to the lever; also to provide a telephonic instrument in which the diaphragm will be confined in place by pressure derived from a lever normally under pressure whereby the diaphragm is rendered more sensitive to vibrations, and whereby any variation in retaining pressure on the diaphragm due to usage, and which in constructions heretofore employed arises from changes taking place in the diaphragm retaining means, is automatically absorbed or taken up; and it has further for its object to simplify and improve the mechanical construction and arrangement of the parts by which they may be more readily assembled and taken apart.

While the invention has been designed particularly for use in telephonic receivers, and a receiver has been selected for the purpose of illustration, yet it is to be understood to include in its scope any and all applications for which it may be adapted.

To the accomplishment of the foregoing and such other objects as may hereinafter appear, the invention consists in the fea-

tures hereinafter particularly described and then sought to be clearly defined by the claims reference being had to the accompanying drawing forming a part hereof and in which:

Figure 1 is a plan view of an instrument, in this instance a receiver, embodying my invention, the top of the receiver box or casing being removed, and Fig. 2 is a side elevation of the same. Fig. 3 is a detail, enlarged scale, of magnet and armature.

In the drawing the numeral 1 designates a permanent magnet, as illustrated being a well known horse-shoe type, upon a pole 2 of which is mounted an induction coil 3, and upon the other pole 4 of which is mounted an armature 5, a small air space 6 being formed between the pole 2 and the armature as illustrated. The armature has an extension or arm 7 which extends beyond the field of the magnet and constitutes a lever whose opposite end bears against a diaphragm 8 of suitable material and which is contained within the plate or disk 9 having, in the receiver type illustrated, the tube 10 to which may be attached a sound distributing horn (not illustrated). The plate 9 may be supported from the magnet 1 by posts 11 and screws 12 with adjusting nuts 13 and 14, or be otherwise supported. Between the diaphragm 8 and its seat in the plate is a ring 15 preferably of soft fibrous material upon which the diaphragm rests. The diaphragm is held in place by pressure from the arm or lever 7 which is held in constant contact with the diaphragm by pressure derived from the pull of the magnet on the armature; the contact being maintained in the back and forth movement or vibration of the diaphragm. For clearness of illustration, the depression in the center of the diaphragm by the pressure exerted by the magnetic pull on the lever is somewhat magnified in the drawing. It will be understood that the pressure may be more or less but should be such that there will be constant contact under pressure between the lever and the diaphragm so that the movement of one will respond to the movement of the other, the lever in its

movement in one direction imparting movement to the diaphragm and when the pressure of the lever is lessened the diaphragm moving in the opposite direction 5 with the lever so that the movement of one responds to the movement of the other. By causing the lever to constantly exert a pressure on the diaphragm the latter is rendered more sensitively responsive to the 10 variations in the magnetic pull due to the fluctuations in the current passing through the induction coil 3. This feature of the invention accordingly in its broadest scope comprehends a diaphragm constantly under 15 the pressure of an arm or lever, the diaphragm and lever being responsive to the movement of each other, and both responsive to variations in an electric current; and in the preferred form the diaphragm 20 being under constant or continuous pressure or tension from magnetic pull transmitted through an arm or lever. Another advantage of having the diaphragm under the constant pressure of the arm or lever 25 is that the diaphragm may be held in place solely by such pressure without the employment of rings or clamps as commonly practised. This makes it possible to more quickly and easily place the diaphragm in 30 place and remove it when necessary, and also causes the diaphragm to be automatically adjusted upon its seat and to be held firmly thereon, so that for mechanical reasons as well as the others mentioned the 35 invention possesses much merit.

The arm or lever 7 may be of any approved form but preferably is of an elbow form as illustrated, and preferably is of steel or other metal, and is readily placed 40 in position by introducing its long arm between the posts 11 and passed between the magnet 1, and plate 9 so that its bent end will bear against the diaphragm while it will have its fulcrum through the armature 45 5 on the pole 4 of the permanent magnet. The magnetism of the magnet will hold the lever securely in place, and as the fluctuations of the current passing through the induction coil 3 will cause variations in the 50 magnetic pull on the armature the lever will quickly respond to such changes in the magnetic pull so that the pressure of the lever on the diaphragm will correspondingly increase or lessen and the diaphragm respond 55 to the receding movement of the lever and as quickly respond to the return movement of the lever when its pressure is increased. A comparatively slight movement of the lever on its fulcrum afforded by the pole of 60 the magnet will be amplified at its end in contact with the diaphragm and the receiver will give forth clear and distinct wave vibrations. While it is not necessary that the end of the lever should be permanently 65 or rigidly connected to the diaphragm be-

cause it is kept in constant contact therewith by the magnetic pull of the magnet, yet it will be understood that it may be rigidly connected to the diaphragm but in such case its relation to the diaphragm 70 should be such that it will constantly exert pressure thereon as particularly described.

I have illustrated and described with particularity the preferred construction and arrangement of the several parts but it will be appreciated that changes can be made therein which will be within the scope of the invention in its broadest interpretation and accordingly I am not to be confined to such preferred construction except where 80 the same is specified in the appended claims. It will also be understood that while I have selected a telephone receiver to illustrate the embodiment of the invention I do not mean to restrict myself thereto when the same 85 features may be otherwise used.

Having described my invention and set forth its merits what I claim is:

1. In a telephone instrument including electro-magnetic means, a diaphragm free at 90 its periphery, a seat therefor, and an arm or lever at all times under magnetic stress for exerting a constant pressure on the diaphragm, said lever and diaphragm being responsive in their movements one to the 95 other.

2. In a telephone instrument, a diaphragm free at its periphery, a seat therefor, an arm or lever exerting at all times a constant pressure on the diaphragm, and means exerting magnetic pull on the arm or lever 100 to impart said pressure to the diaphragm.

3. In a telephone instrument, a diaphragm free at its periphery, a seat therefor, a magnet, and means for transmitting at all times 105 a constant pull of the magnet on the diaphragm to hold it in operative position.

4. In a telephone instrument, a diaphragm free at its periphery, a seat therefor, an elbow lever connected with the diaphragm, and a magnet actuating the lever to exert 110 at all times a constant magnetic stress on the lever through which it is transmitted to the diaphragm.

5. In a telephone instrument, a diaphragm, and a lever resting freely upon a magnetic fulcrum and having one end in free contact with the diaphragm and normally under magnetic stress for pressing it against the diaphragm to hold the diaphragm in 115 operative position by such pressure.

6. In a telephone instrument, a diaphragm free at its periphery, a seat for the diaphragm, and a lever having one end in operative connection with the diaphragm and at all times under magnetic strain for holding 120 the diaphragm in place toward its seat.

7. In a telephone instrument, a diaphragm free at its periphery, a seat therefor, a lever holding the diaphragm in operative position 130

by pressure on the diaphragm, and a magnet exerting a magnetic pull on the lever at all times to press it against the diaphragm.

8. In a telephone instrument, a diaphragm free at its periphery, a seat therefor, a lever holding the diaphragm in operative position by pressure on the diaphragm, a magnet exerting a magnetic pull on the lever at all times to exert a constant pressure of

the lever on the diaphragm, and electrical means for varying the electrical pull of the magnet.

In testimony whereof I affix my signature in presence of two witnesses.

WILLIAM PRESTON STUNZ.
